(57) **CLAIM**

The ornamental design for a display screen or portion thereof with animated graphical user interface, as shown and described.

DESCRIPTION

FIG. 1 is a front view of a first image of a display screen or portion thereof with animated graphical user interface showing our new design;

FIG. 2 is a front view of a second image thereof;

FIG. 3 is a front view of a third image thereof; and

FIG. 4 is a front view of a fourth image thereof.

FIG. 5 is a front view of a fifth image thereof; and,

FIG. 6 is a front view of a sixth image thereof.

The appearance of the image transitions sequentially between the images shown in FIGS. 1-6. The process or period in which an image transitions to another forms no part of the claimed design.

The broken lines showing of the display screen, images and text form no part of the claimed design.
